UNITED STATES PATENT OFFICE

2,506,355

ADJUSTABLE REFLECTOR SUPPORT

Joseph Guercio, Chicago, Ill., assignor to
William Waltz, Chicago, Ill.

Application March 27, 1946, Serial No. 657,548

2 Claims. (Cl. 248—278)

1

This invention relates to reflectors and means for adjusting them, to get the proper reflection.

According to the principle of my invention, I have provided simple adjusting means for accurately adjusting reflectors.

This means relates not only to means for vertical adjustment, but also to lateral adjustment.

I have illustrated my invention by means of a projector, as shown in Fig. 1, which throws an image horizontally to a first inclined reflector, which reflects the image, in turn, to a second inclined reflector, which, in turn, reflects the image to a ground screen, or the like.

As will be more apparent hereafter, I have provided a reflector which is hinged at the top, and a screw and knurled nut, which is adapted to press against the bottom of the reflector, for vertical adjustment on the hinge aforesaid.

For lateral adjustment, I have provided another screw, which is adapted to be turned to press against one side of the reflector, to effect lateral adjustment.

I have also provided spring arrangements for the reflectors, whereby, on the threading of the screws in the opposite direction, the springs will cause the reflectors to move in the opposite direction.

Further objects and advantages will appear and be brought out more fully in the following specification, reference being had to accompanying drawings, in which:

Fig. 1 is a vertical sectional view of the device.

Fig. 2 is a front elevation of the same as viewed from the right in Fig. 1.

Fig. 3 is a perspective of the reflector adjusting means.

Fig. 4 is a vertical section through the adjusting means.

Fig. 5 is a horizontal section on line 5—5 of Fig. 4.

Referring to the drawings in detail, in which I have selected the preferred form for the purpose of illustrating the principle of my invention, I have shown a housing 10, containing a projector 11 and a reflector holder 12, carrying a reflector, which is adapted to reflect pictures upon another reflector 13, which, in turn, is adapted to reflect them onto ground glass 14 or other translucent screen, as will be readily understood by those skilled in the art.

The holder 12 is hinged, as at 15, to an adjusting plate 16.

The adjusting plate itself is hinged, as at 17, to the front wall 18 of the projector.

The adjusting plate 16 is connected by a spring 19 to the front wall 18.

The reflector holder 12 has an ear 20, which is connected by a spring 21 to the front wall 18 of the housing.

The reflector holder also has a flange 22, and a

2

second flange 23 bent at right angles to the flange 22.

An adjusting screw 24, having a knurled head 25, is adapted to be threaded through the front wall 18, against the right-angled flange 23, to give movement and adjustment in a horizontal plane.

When the reflector is manipulated by the screw 24, it will turn upon the hinge 15, as clearly shown in Fig. 5.

In addition to the horizontal adjustment, I have provided for vertical adjustment by a screw 26, also having a knurled head, which is screwed through front wall 18 and against the adjusting plate 16; and, which, as has been said, is hinged as at 17.

The result of this is that, upon screwing the screw 26 in one direction, the adjusting plate 16 will be moved in one direction, and when the screw 26 is moved in the opposite direction, then the spring 19 will pull the adjusting plate 16 in the opposite direction also.

With respect to the reflector 12, when it is desired to withdraw the screw 24, then the spring 25 21 will pull the reflector in the opposite direction.

In operation, when the reflector carried by holder 12 is in properly-adjusted position, the image projected from the projector 11 will be reflected by it onto said reflector 13, which, in turn, will project the image onto the translucent screen 14, the image being sufficiently enlarged in traversing the course indicated above. As the projector 11 may be removed or replaced as the occasion arises, the adjustments of the reflector carried by holder 12 enable proper centering of the image on the screen 14, without disturbing the projector 11. By turning screw 25 inwardly, the reflector is tilted so as to project the image onto reflector 13 and accurately center it thereon; and by adjusting screw 26 inwardly, the reflector is moved to adjust the image vertically on the reflector 13.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. A device of the character described, comprising: a reflector control, including a support; a first element pivoted to move about one axis with respect to said support, and a second element adapted to carry a reflector, pivoted to said first element about an axis at an angle to said

first axis; yieldable means normally urging each of said elements in a predetermined direction; and set screws carried by said support and opposing said yieldable means for independently adjusting each of said elements with reference to said support.

2. A device of the character described, comprising: a support; a plate-like member hingedly connected along one edge to said support; a second plate-like member hingedly connected along one edge to a free edge of said first plate-like member, said second plate-like member having means for the accommodation of a reflector; a spring normally urging said first plate-like member toward said support; a second spring normally urging said second plate-like member toward said support; a set screw carried by said support and bearing on said first plate-like member; and a second set screw carried by said support and bearing against said second plate-like member. 20
